UNITED STATES PATENT OFFICE.

EDWARD J. TRIAY, JR., OF JACKSONVILLE, FLORIDA.

LACE-LOCKING MEANS FOR ARTICLES OF PERSONAL WEAR.

Application filed August 11, 1922. Serial No. 581,116.

To all whom it may concern:

Be it known that I, EDWARD J. TRIAY, Jr., a citizen of the United States, a resident of Jacksonville, in the county of Duval and 5 State of Florida, have invented certain new and useful Improvements in Lace-Locking Means for Articles of Personal Wear, of which the following is a specification.

In many articles of personal wear, such 10 as shoes, corsets and the like, including surgical bandages, it is frequently necessary, or desirable, to bring the lacing edges closer together in certain zones than in other zones.

15 It has been the custom, in connection with corsets, for the wearer to tie knots in the lacing string so as to hold the lacing edges at a predetermined juxtaposition so that a given pressure or shape is maintained within 20 in that zone irrespective of the other zones of the lacing edges.

In the case of shoes equipped with my invention, the use of arch supports and the like may be eliminated inasmuch as the shoe 25 may be drawn to a snug fit around the foot and this fit maintained at all times while the shoe is on the foot; while the lacing in other zones may be comparatively loose.

Frequently in the case of surgical bandages, it is desirable to have certain zones of the bandage much tighter than other zones. This can readily and efficiently be accomplished by my invention.

My invention may be efficiently used in 35 connection with many other articles.

The object of my invention is to provide a lacing edge with means whereby said edge can be drawn much tighter in certain zones than in others without affecting the pliability of adjacent edges in other zones in 40 the same article.

My invention consists of a lacing edge provided throughout its entire length or in predetermined zones with means for 45 locking the lacing string against movement after said string is once adjusted in a given lacing eyelet.

This is a division of my application Serial No. 529,242 filed January 14, 1922 on 50 which Patent No. 1,434,723 issued November 7, 1922.

In the drawings:

Figure 1 is a detailed view of a portion of a shoe showing my invention applied 55 thereto,

Fig. 2 is a similar view of a corset,

Fig. 3 is a top plan view of Fig. 4,
Fig. 4 is a side elevation of Fig. 3,
Fig. 5 is a vertical central section of 60 Fig. 4,

Fig. 6 is a rear elevation of Fig. 5.
While I have selected certain articles of 65 wearing apparel for the purpose of illustrating my invention, it will, of course, be understood that my invention is susceptible of efficient use with many other articles, including surgical bandages.

Reference numeral 1 is a shoe having the 70 lacing edge 2 provided with eyelets 3 and hooks 4.

The hooks 4 comprise a main body having an angular groove 8 within which the material of the lacing edge is adapted to be clamped.

In numerous instances it is necessary, or 75 desirable, to draw the edges of the lacing strips 2 very closely together in the proximity of the instep of the foot, and maintain them in that position while the shoe is in use. It is impossible to do this with the 80 present construction of eyelets and hooks provided in shoes, and in the effort to do it, the shoe is uncomfortably tightly laced around other portions of the foot and ankle, whereas by the use of my invention the lacing edge 2 may be brought closely together 85 at the lower zone of the lacing edges and when in that position the lacing string 5 is tightly wedged within the hooks, and locked against relative movement through 90 the hooks; whereby a predetermined position of proximity of the lacing edges within that or any other zone is maintained. This possible adjustment of the lacing edges enables one to draw the shoe snugly around 95 the foot, thereby supporting the foot and making it possible for one to discard the use of the usual so-called arch supports, because the shoe can thus be maintained in this predetermined close fit as a support for the arch 100 of the foot.

To meet the wishes of those who may desire to use what is known as hook eyelets for shoes, I have designed the construction of hook shown, and in this construction the hook is provided with a depending wedging edge 6.

This locking edge 6 may be formed by depressing the material of the hook as clearly shown in Figs. 3, 4, 5 and 6.

What I claim is:

1. In an article of personal wear having

free lacing edges adapted to be secured in proximity to each other, of a series of lacing hooks having a lace locking member near the said free edges, said locking member adapted to receive and lock a lacing string against movement after the desired tension has been placed upon the string to hold the said free edges at the desired distance apart at any selected zone at intervals throughout the length of the said free edges.

2. In an article of personal wear having free lacing edges adapted to be secured in close proximity to each other, of a series of

lacing eyes secured to said lacing edges, and a series of locking hooks also secured to said free edges and having a lace locking member, said locking member of the hooks being adapted to receive and lock a lacing string against movement relatively thereto after the desired tension has been placed upon the string to hold the said free edges at the desired distance apart at any selected zone at intervals throughout the length of said free edges.

In testimony whereof I affix my signature.
EDWARD J. TRIAY, JR.
